AGITATING ELECTROPLATING MECHANISM

Charles L. Fread, Adrian, Mich., assignor, by mesne assignments, to Gerity-Michigan Corporation, Adrian, Mich., a corporation of Michigan

Application December 29, 1945, Serial No. 637,849

2 Claims. (Cl. 204—202)

1

The present invention relates to electroplating tanks and means for agitating the work in the electroplating solution within the tank as the work is progressively moved from one end of the tank to the other during the plating process, thereby speeding up production and greatly enhancing the efficiency and success of the plating action.

An object of the invention is to provide an efficient mechanism of this character in which a continuous production of plated articles is afforded and where means are used to suitably support the work within the tank on means carrying the same horizontally lengthwise of the same with means also operating to vertically move the articles within the electroplating solution in a simplified and smoothly operating manner.

In one embodiment of this invention, the work is moved along by endless conveyors, and at the same time vertically reciprocated by a push rod mechanism operated by eccentrics driven from a power shaft and absorbing means are also used to cushion the action of the eccentrics, thereby smoothing the operation of the mechanism throughout thereby eliminating irregular jerking movements, jolts and jars and heavy wear consequent thereto upon the entire mechanism.

Further objects and advantages are within the scope of this invention such as relate to the arrangement, operation, and function of the related elements of the structure, to various details of construction and to combinations of parts, elements per se, and to economies of manufacture and numerous other features as will be apparent from a consideration of the specification and drawing of a form of the invention, which may be preferred, in which:

Figure I is a top plan view of our agitator tank;

Figure II is a side elevation;

Figure III is a transverse sectional view on the line III—III of Figure II;

Figure IV is a detail of the chain and cathode rod connections;

Figure V is an enlarged side elevation of the eccentric drive and shock absorbing means;

Figure VI is a top plan view of the driving connection for the agitating means;

Figure VII is an enlarged sectional view on the line VII—VII of Figure V;

Figure VIII is a front vertical elevation of Figure VII;

Figure IX is a sectional detail of the buss bar and push rod assembly; and

Figure X is a sectional view on line X—X of Figure V showing the shock absorber.

The agitator mechanism for the electroplating tank 10 includes the two copper buss bars B, one carried on each side of tank 10 at the top, which buss bars carry the transversely arranged cathode rods 12. Since the buss bars B recipro-

2

cate vertically, as will hereinafter be fully set forth, the current is led in to the buss bars B by flexible connectors C illustrated in detail in Figure VIII. These flexible connectors C are connected to a stationary lead in fixed buss bar 11, insulated from the rest of the entire machine, the fixed buss bar 11 being connected with any suitable source of power. The articles being plated, or the work W, is hung down from rods 12 into the plating solution in tank 10 as shown in Figure III.

An endless chain conveying mechanism 20 moves the work W lengthwise of the tank 10 and to this end we use a suitable gearing 22 with a drive mechanism 23 for connecting the chain conveyor 20 through said gearing with an electric driving motor 24. The work W is directly carried by the cathode rods 12 which, while resting on buss bars B, are pushed along over the tank while the work W is submerged in the solution as indicated. In order to move the cathode rods 12 longitudinally of the tank from the chain conveyor 20, we provide at spaced intervals along the chain, pushers 31 fixed to the chain as shown in Figure 4 and adapted to contact an insulated bushing 32 connected to the cathode rods 12 illustrated in Figure VII. The rods 12 are prevented from sliding transversely by a square block 34 recessed at 35 for sliding the cathode rod on the buss bar B. At the same time the rods 12 have a satisfactory electrical contact with the bars B.

An important feature of our invention is the means to agitate the work W vertically as it progresses through the solution in the tank 10. It is desirable to keep the surface of the work free from anything interfering with the uniform action of the electrolytic deposit, such as gas formation, bubbles and the like and the vertical reciprocation of the work—particularly the downward movement operates to prevent gas formation and to dislodge any bubbles formed, thus facilitating a uniform electrolytic action. To this end, the buss bars B, and consequently the cathode rods 12, are reciprocated vertically as the rods 12 move the work longitudinally through the tank. A satisfactory mechanism for reciprocating the buss bars B, we have found in a series of vertical push rods each operated by an eccentric mechanism as indicated in Figures III, VII, VIII, and IX. We arrange two pairs of power driven shafts S extending along the opposite sides of tank 10, each shaft having at spaced intervals thereon, eccentrics 40 secured to shafts S, said eccentrics 40 forming means with suitable reciprocating push rods or connections to move buss bars B up and down which in turn vertically reciprocates the cathode rods and hence the articles to be plated or the work W. Referring to Figures VII and VIII, one of the push rods 42 is shown as slidably mounted in

bearings 43 and 44 carried on the outside of the tank 10, as by channel plates 45 and uprights 46. The lower end of push rods 42 have heads 48, preferably hardened for contact with and operation from the eccentric cams 49.

The copper buss bars B are each insulatingly and slidably carried or guided alongside the top of tank 10 by the detail shown in Figure IX. Here, the upper channel iron 50 is welded or otherwise secured to tank 10 and has bolted thereto insulation plates or fiber blocks 52 at spaced intervals along the tank 10 above the eccentrics 49. On the outside of bars B a similar insulation or fiber block 54 is carried by the upper end of the vertical braces 46, the lower end of the latter being secured to the lower channel plate 45 as indicated in Figure VII. The upper ends of the push rods 42 are rounded off as indicated at 42' in Figure IX to suitably contact a bumper plate 56 insulated at 57 and carried on the bottom edge of the bus bars B.

Another important feature of our invention is the employment of means to absorb the shock and cushion the operation of the entire mechanism. As the eccentrics go over dead center and the load (including all the work) the cathode rods and the buss bars are released from an upward thrust to a downward movement, the weight when fully loaded amounting in many instances to thousands of pounds. We therefore provide hydraulic shock absorbers 60 insulatingly connected at the top with buss bars B and insulated at the bottom connection with the fixed channel plates 45, located at spaced intervals along the tank between the several eccentrics 49. A satisfactory shock absorber for this purpose is shown in Figure X insulatingly connected at the top by bolt 61, insulating grommet 62 to buss bar B. At the lower connection a bolt 65, connected to the other working part of the absorber 60 through insulation 66 is secured to angle iron 67 which in turn is bolted or otherwise secured to channel 45.

The details of the shock absorber 60 shown in Figure X includes a sleeve 70 carrying the grommet 62 on head 71 secured to the buss bar B by bolt 61 as stated. The head 71 carries a piston 73 within the inner cylinder 75 of the shock absorber proper, the other casing 76 thereof being provided with head 77 connected to bolt 65 and hence to channel 45. The piston 73 has suitably arranged openings therein as at 78 to resist movement of the working fluid in one direction to absorb the shocks employing the check valve mechanism 79 but permitting free movement of the parts in the other direction as typical of the operation of hydraulic shock absorbers.

The work W as stated is moved through the tank 10 by an endless conveyor mechanism and the upper part of endless chain 20 rides along the bottom of the upper channel 50 as shown in Figure VII and on top of the lower channel 45. The motor 24 is connected by a suitable chain drive mechanism 25 and speed reduction mechanism to the sprocket wheel 21 of the endless chain 20. As shown in Figure I, at one end of tank 10, a shaft 27 drives the sprocket wheel for a similar chain 20 on the other side of the tank 10.

The mechanism for driving the eccentric shafts S include an electric motor 80, (Figure I and Figure II) drive 81 to gearing 82 connected to sub shaft wheel 85, and as shown in Figure VI more in detail, the shaft 87 of wheel 85 drives sprocket 88 for chain 90 and overhead shaft

91 (see Figures I, II and III) driving chain 90' on the other side of tank 10. Referring to Figure VI, a gear box 100 contains a set of bevel gears 101, 102, each adapted to be driven from gear 103 on shaft 87, in turn driven by wheel 85 connected to the power as stated supra. Each bevel 101, 102, drives stub shafts 110 and 111, the latter arranged to drive eccentric shafts S, as indicated. A duplicate of the gear box 100 and drive for shafts S is located on the other side of the tank 10, as shown in Figure III in which case the gear 85 is driven from chain 90'.

I claim:

1. In combination with an apparatus for moving work pieces longitudinally through an elongated electroplating tank comprising an endless chain at each side of said tank, power carrying buss bars at each side of said tank, work holding electrode rods spanning said tank from side to side, means for supporting the ends of said electrode rods upon the buss bars and in constant sliding contact therewith, and means attached to said endless chains for sliding said electrode rods along said buss bars, eccentric means to impart vertical reciprocation to said buss bars while the rods remain in sliding contact therewith, and shock absorbers mounted on said tank and attached to said buss bars to partially restrain the downward movement of said buss bars and said electrode rods.

2. In combination with an apparatus for moving work pieces longitudinally through an elongated electroplating tank comprising an endless chain at each side of said tank, push members extending upwardly from each of said chains and in pairs at opposite sides of said tank, power carrying buss bars at each side of said tank, work holding electrode rods spanning said tank from side to side and carried by said buss bars, insulating members on said rods interposed between the rods and said push members, mechanism for moving the chains whereby said rods are moved longitudinally of said tank, and means to support the ends of said electrode rods in constant sliding contact with each of said buss bars, means to impart vertical movement to said buss bars including a plurality of synchronously driven eccentrics, and hydraulic shock absorbers attached to said buss bars so as to partially relieve said eccentrics of the weight of the bars and work during the downward movement of the bars.
